COMBINED SHIELD AND STAND FOR OXY-GAS TORCH

Robert Whitney, Brooklyn, N.Y., assignor to Eutectic
Welding Alloys Corporation, a corporation of New
York

Filed Nov. 16, 1964, Ser. No. 82,619

Term of patent 14 years

(Cl. D62—2)

*Fig.3.*FIG. 1 is a side elevational view of a combined shield and stand for an oxy-gas torch showing of my new design; FIG. 2 is a top plan view thereof; and FIG. 3 is a front elevational view thereof. The dotted line showing is for illustrative purposes only. I claim: The ornamental design for combined shield and stand for oxy-gas torch, as shown and described.
